WILLIAM E. HASKELL, OF BRATTLEBORO, VERMONT, ASSIGNOR TO ESTEY ORGAN COMPANY, OF BRATTLEBORO, VERMONT, A CORPORATION OF VERMONT.

ORGAN-PIPE.

971,502.

Specification of Letters Patent. Patented Sept. 27, 1910.

Application filed February 10, 1910. Serial No. 543,050.

To all whom it may concern:

Be it known that I, WILLIAM E. HASKELL, of Brattleboro, in the county of Windham and State of Vermont, have invented certain 5 new and useful Improvements in Organ-Pipes, of which the following is a specification.

The present invention consists in a novel construction of a reed pipe for pipe organs 10 the effect of which is to supply a resonator having the capacity and quality of the usual resonator but being materially less in height. Accordingly, it is practicable to supply a 15 pipe organ with reed pipes of low pitch in apartments where the height is not sufficient for such pipes of orthodox construction. This result is accomplished without requiring any greater space laterally for the resonator; indeed, on the contrary, the improved 20 resonator may be less in its extreme lateral dimensions than the old style resonator.

The improvement is illustrated in the accompanying drawings wherein—

25 Figure 1 is a vertical longitudinal section of a reed pipe with the improved resonator. Figs. 2 and 3 are diagrammatic views illustrating variations in the lineal proportions of the improved resonator.

30 Except for the improvement in the resonator, Fig. 1 illustrates a common type of reed pipe with a striking reed.

A is the reed or echalote with its upper open end fixed in the passage of the block B, 35 and communicating through it with the base C of the resonator. The vibrating tongue or languette D is secured firmly against the upper part of the reed by means of the wedge E.

40 F is the tuning wire; and G is the boot which incloses the reed and tongue and forms the chamber which conveys the compressed air from the windchest to the reed through the inlet hole g, at its bottom. The 45 boot has its wind outlet solely through the reed A, and otherwise has no outlet at its upper end.

The base C of the resonator is conical, 50 diverging upwardly, with its largest end uppermost, and it is open top and bottom.

As shown, all of the cross sections of the base are circular, and it is made of thin sheet metal of the ordinary composition used in metallic organ pipes. Instead, how- 55 ever, of the resonator extending upwardly to

the full height necessary for the pitch of the reed, it is cut off at any desired level and the loss in height is compensated for by the inverted sheet metal bell H. The base C of the resonator is open at its top as shown at 60 a and the bell H is open at its bottom b and has a closed top c. The bell H is of uniform area in cross section throughout its length, and in the illustrated construction it is cylindrical and all of its cross sections are 65 circular.

The bell can be supported in any convenient manner. As illustrated, a screw threaded stem I is soldered to the upper end of the resonator base C and extends through a hole in the top c of the bell. This screw-threaded stem I carries an adjustable nut J, upon which the under side of the top c rests. The nut J, can be adjusted on the screw I thereby governing the distance of 70 the top of the bell above the open top of base C. A spring K, soldered on the interior of the bell H bears against the exterior of the base C and prevents any objectionable movement of the bell. A second nut J can 75 be (as shown) above the top c of the bell.

The area in cross section of the interior of the bell should be twice the interior area of the base C at its top. If thin metal is used for the base, it can be ignored in computing 80 the areas, although the nearer that exactitude is obtained the more perfect will the result be. The area of the annular passage connecting the open top of the base with the interior chamber of the bell should be just 85 equal to the area of the base at its top; and this is secured by making the distance between the top edge of the base and the bottom surface of the top c of the bell one-quarter the interior diameter of the base at 90 its top. It is important that the bell should be of uniform area in cross section when used with the tapering or conical base since this gives a gradually increasing area to the 95 chamber between the bell and the resonator thus giving the same effect as if the tapering base were carried upwardly to the orthodox height of the resonator.

The relative lengths of the base and the bell can be varied without affecting the purpose of the resonator as a whole, and different proportions are shown in Figs. 1, 2 and 3. Fig. 3 shows in dotted lines the height of the resonator C if it should be extended to the level L, in the heretofore well- 100 105 110

known way. In the improved construction the resonator can be cut off at any height and the bell can compensate for the cut-off portion. For example, as shown in Fig. 3 the base is shown terminating at the level X, and the bell H is of the same height as the portion cut off; that is, its height is equal to the distance between the levels X and L. So, the resonator can be cut off at any point and compensation can be made by the bell. For example, Fig. 2 shows the resonator cut off at the level shown at Y in Fig. 3 and in this case the bell H is of the same height as the cut off portion of the resonator shown in Fig. 3 between the levels L and Y. Fig. 1 shows a resonator base proportional to that of Fig. 3 if terminating at the level Z and the bell of Fig. 1 is proportionately equivalent to the cut off portion between the levels L and Z of Fig. 3. In all these instances, the internal area of the inverted bell is just twice the internal area of the base at its open top, and the bell is of equal areas in cross-section throughout its length.

It is obvious, that the lateral dimensions of the resonator need not be increased as a result of the presence of the bell and indeed may be reduced. It is obvious, for example, that in the construction shown in Fig. 2, the lateral dimensions are less than those of a full height resonator indicated at its top by dotted lines in Fig. 3. With the proportions shown in Fig. 1 the lateral dimensions of the bell are somewhat smaller than would be the lateral dimensions of the top of the resonator if extended up in the old way. Fig. 3 shows the bell greater in lateral dimensions than the resonator if extended up in the old way, but shows a construction, in this respect, which would probably not be used in practice, the figure being introduced to aid in explanation of the principle of the new construction, rather than showing a commercial form. Likewise, Fig. 2 illustrates a construction in which there would be a variation in the quality of the resonance owing to the bell extending down around the boot. It is a construction, however, which can be practically used in case diminution in height to that extent is necessary. If practicable, however, the bell should not extend below the top of the boot, nor far enough down to interfere with the manipulation of the tuning wire.

While the improvement is illustrated in connection with a pipe having a striking reed it is also applicable to the resonators of pipes having free reeds. The resonator constructed as set forth has two chambers, one within the base, the other between the base and the bell, and these two chambers extend lengthwise and alongside each other and they communicate at their upper ends.

I claim—

1. A striking reed organ pipe having a resonator comprising a sheet metal conical base open at top and bottom with its large end uppermost, and a sheet metal cylindrical inverted bell open at its bottom and closed at its top, said bell surrounding the upper end of the base and being supported thereby, the internal area of the bell in cross-section being twice the internal area of the base at its top, and the vertical distance between the top edge of the base and the underside of the top of the bell being one-fourth the internal diameter of the base at its top.

2. A reed organ pipe having a resonator comprising a conical base open at top and bottom with its large end uppermost, and a cylindrical bell open at its bottom and closed at its top, said bell surrounding the upper end of the base and being supported thereby, the internal area of the bell in cross-section being twice the internal area of the base at its top, and the vertical distance between the top edge of the base and the underside of the top of the bell being one-fourth the internal diameter of the base at its top.

3. A reed organ pipe having a boot with a wind outlet through the reed and to the resonator but otherwise closed at its top; and a resonator comprising a conical base open at top and bottom with its large end uppermost, and a cylindrical bell open at its bottom and closed at its top, said bell surrounding the upper end of the base and being supported thereby, the internal area of the bell in cross-section being greater than the external area of the base at its top, and there being a space between the top of the bell and the top of the base.

4. A reed organ pipe having a boot with a wind outlet through the reed and to the resonator but otherwise closed at its top; and a resonator comprising a conical base open at top and bottom with its large end uppermost, and a cylindrical bell open at its bottom and closed at its top, said bell surrounding the upper end of the base and the internal area of the bell in cross-section being greater than the external area of the base at its top, and there being a space between the top of the bell and the top of the base.

5. A reed organ pipe having a boot with a wind outlet through the reed and to the resonator but otherwise closed at its top; and a resonator comprising a base open at top and bottom, and a closed-top bell surrounding the upper end of the base, the bell being of greater dimensions laterally than the top of the base, and there being a space between the top of the bell and the top of the base.

6. A reed organ pipe having a resonator comprising a base open at top and bottom and a bell with an open bottom and an integral closed top, said bell surrounding the

upper end of the base, and there being a space between the top of the bell and the top of the base through which they communicate.

5 7. A reed organ pipe having a boot with a wind outlet through the reed and to the resonator but otherwise closed at its top; and a resonator comprising a tubular base open at top and bottom, and a closed-top bell surrounding the top of the base and communicating at its upper end with the interior of the base.

10 8. A reed organ pipe having a boot with a wind outlet through the reed and to the

resonator but otherwise closed at its top; ¹⁵ and a resonator with two lengthwise extending chambers alongside each other and separated from each other by a common wall only and communicating directly with each other at their upper ends only.

20 In witness whereof, I have hereunto signed my name in the presence of two subscribing witnesses.

WILLIAM E. HASKELL.
